(57) CLAIM

The ornamental design for a display screen with icon, as shown and described.

DESCRIPTION

FIG. 1 is a front view of a display screen with icon of a first embodiment showing our new design;

FIG. 2 is a front view of a display screen with icon of a second embodiment showing our new design; and,

FIG. 3 is a front view of a display screen with icon of a third embodiment showing our new design.

The broken lines showing of the display screen form no part of the claimed design.

1 Claim, 3 Drawing Sheets

FIG. 1

FIG. 3
